(57) **CLAIM**

The ornamental design for a haircut fade tool, as shown and described.

DESCRIPTION

FIG. 1 is a top-front-left perspective view of a haircut fade tool showing my new design;

FIG. 2 is a top-rear-left perspective view thereof;

FIG. 3 is a bottom-front-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof;

FIG. 10 is a left elevational view thereof; and,

FIG. 11 is a right elevational view thereof, showing the head of the haircut fade tool in a tilted configuration.

The broken lines illustrate portions of the haircut fade tool and form no part of the claimed design.
